HACKER FOR TURPENTINE TREES

Filed May 16, 1927

UNITED STATES PATENT OFFICE

EDWIN A. MCKOY, OF NEW ORLEANS, LOUISIANA

HACKER FOR TURPENTINE TREES

Application filed May 16, 1927. Serial No. 191,756.

This invention relates to hackers for turpentine trees and has for an object to provide an implement of the kind having improved means for replacing blades therein in case of wear or breakage.

A further object of the invention is to provide in a device of the kind, a blade so constructed of a substantially uniform thickness as to receive a uniform temper throughout its extent, thereby eliminating the danger of breakage from lack of uniformity in temper.

A further object of the invention is to provide in an implement of the kind improved means whereby the handle may be made to correspond to the wishes of the operator as to length without change in construction other than merely sawing off parts to the required length.

A further object of the invention is to provide a replaceable and interchangeable blade structure which may be employed with various types of holders for the structure and handle.

A further object of the invention is to provide various types of holders for the interchangeable blade structure.

With these and other objects in view, the invention comprises certain novel parts, elements, units, combinations, constructions, interactions and functions as disclosed in the drawings together with equivalents thereof as will be hereinafter more fully described and claimed.

In the drawings:

Figure 1 is a view in elevation of one type of blade holder, disassociated from the handle.

Figure 2 is a view of the blade holder in edge elevation.

Figure 3 is a perspective view of the handle modified to correspond to the present invention.

Figure 4 is a view of the ball or weight used upon the end of the handle.

Figure 5 is a view partly in edge elevation and partly in section of a modification of the blade holder.

Figure 6 is a view in side elevation of an assembly of certain types of the present invention.

Figure 7 is a view in side elevation of the blade.

Figure 8 is a view of the blade in edge elevation.

Figure 9 is a transverse sectional view through the blade and its holder as indicated by line 9—9 of Figure 6.

Figure 10 is a sectional view through the blade and blade holder as taken on line 10—10 of Figure 6.

Figure 11 is a view of a modified type of blade holder to be employed with a handle of the present type of construction and operation.

Figure 12 is a transverse sectional view similar to Figure 10 showing a modification.

Like characters of reference indicate corresponding parts throughout the several views.

The hacker disclosed in the present application is in general respects similar and corresponds to the hackers already employed in turpentine culture, an assembly being shown of present use.

According to the present invention, the handle 20 will be provided with a longitudinal bore 21 through which may be inserted the rod 22 of the type shown at Figures 1 and 2 or the threaded extension 23 and bolt 24 of the type shown at Figure 5. In either case, the rod or extension is provided with a blade holder or head 25 having a channel formed therein bound by the shoulders 26 and 27 and provided with a perforation 28. Into this channel so formed by the shoulders the blade is inserted, the shank 29 fitting snugly against the shoulders 26 and 27, the perforation 30 registering with the perforation 28 and secured therein by any usual

and ordinary means as the bolt 31. The blade is curved at 32 to correspond to the present practice in hacker blades and is provided with an offset 33 which fits against the beveled edge 34 of the holder so that substantially a smooth surface is presented offering no obstruction to the passage of chips loosened by the use of the hacker.

The same effect is accomplished by beveling the holder as indicated at 25', Figure 12, and the hacker is provided with no offset, being a straight shank with curved blade 32'.

The end of the rod opposite the head 25 or 15 the bolt 24 is intended to pass through the usual weight or ball 35, said ball being provided with a perforation for that purpose. In the type employing the rod and shown at Figures 1 and 2, a nut 36 will be applied 20 to the threaded portions 37 of the rod holding the ball 35 rigidly against the end of the handle 20 as well as drawing the head 25 into the radial groove 38 in the end of the handle, preventing the blade from rotating 25 relative to the handle when in use.

It is obvious that, when the type of holder is used as shown at Figure 5, the bolt head 39 will abut against the outer surface of the weight or ball 35. With the use of the latter 30 type, the handle 20 may be sawed off to any length desired but with the use of the type shown at Figures 1 and 2, after the handle has been sawed to the required length it may also be necessary to saw off the threaded part 37 so that no undesirable length extends beyond the nut 36.

Also, it is to be understood, that while in the type shown at Figure 5 a head 39 is represented, any usual and ordinary mechanical 40 equivalent will be within the scope of this invention as, for instance, threading the rod 24 its entire length at both ends and applying a nut thereto instead of a head. This is merely an ordinary mechanical equivalent 45 and its illustration is not considered necessary.

So that the replaceable and interchangeable blades may be used with substantially the structure at present in use, a modification 50 is shown at Figure 11 having a tang 40 with a hook 41 of substantially the usual and ordinary type. In this case the blade is inserted between the shoulders 26' and 27' exactly as in the constructions shown in the 55 other figures, this being merely a modification to enable the users to employ the replaceable and interchangeable blades without otherwise changing the general form of implements in use.

60 What I claim to be new is:

A hacker comprising a blade holder embodying spaced upstanding shoulders and with a perforation intermediate the shoulders, a blade proportioned to fit snugly between the shoulders and having a perfora-

tion registering with the perforation of the holder, means inserted through the perforation to lock the blade rigidly relative to the holder, a handle provided with a longitudinal bore, a threaded extension formed upon the blade holder at an acute angle to the shoulder and proportioned to be inserted into the bore, and means to lock the extension into the handle.

In testimony whereof I affix my signature.

EDWIN A. McKOY.
